UNITED STATES PATENT OFFICE.

GEORGE A. BURNHAM, OF SAUGUS, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

MULTIPOLE-ELECTRIC-SWITCH CASING.

Application filed August 18, 1921. Serial No. 492,809.

This invention relates to oil immersed electric switches.

It is desirable to provide certain types of switches with a relatively large body of oil and a relatively large gas expansion space above the oil in the switch and also preferably with a relatively restricted body of oil about the switch-members in the vicinity of the circuit-interrupting arc, whereby to improve the circuit-interrupting properties of the switch.

An object of this invention is to provide a multipole switch with means to restrict the body of oil adjacent the circuit-interrupting arc of each pole and means to contain a body of oil common to all poles, and an expansion space above the oil common to all poles of the switch.

A further object is to provide an oil receptacle having a plurality of restricted compartments each adapted to contain a pole of the switch all open at the bottom for oil communication and all open at the top for gas communication.

A further object is to provide means contained within the oil space in the receptacle and extended between and fixed to opposite side walls of the receptacle to tie in the opposite side walls whereby to provide a structure adapted to resist elevated internal pressures.

A further object is generally to improve the construction and operation of an oil immersed electric switch.

Fig. 1 is a sectional elevation of a multipole electric switch embodying the invention.

Fig. 2 is a top view looking down into the oil receptacle.

Fig. 3 is a sectional elevation of an oil receptacle embodying the invention taken along line 3-3 of Fig. 2.

As here shown the switch embodying the invention includes the switch frame 10 carrying the sets of switch-members comprising the stationary switch-members 11, 12 and 13 and the corresponding movable switch-members 11^a, 12^a, and 13^a, each set of which constitutes a pole of the switch. Operating mechanism 14 is associated with said movable switch members.

An oil receptacle 15 depends from said switch frame; and said frame constitutes a cover for the receptacle. Said receptacle may be secured removably to the frame by

the bolts 16 carried by the receptacle, and the 55 wing nuts 17.

Said receptacle is divided into the oil compartments A, B, and C each adapted to contain a pole of the switch; and the oil receptacle may be divided into as many compartments as there are poles of the switch.

Each compartment comprises a cell 20 formed of suitably strong material as sheet steel. Each cell is of suitable length and may have the substantially parallel side 65 walls 20^a and the more or less cylindrical end walls 20^b for increased strength. Said cells are placed side by side within the oil receptacle 15 and preferably have such dimensions, with relation to the receptacle, 70 that the contiguous side walls 20^a of the cells are in contact and the side walls of the end cells are in contact with the front and rear walls of the oil receptacle. Preferably, also the end walls 20^b are in contact with the side 75 walls of the oil receptacle. Said cells may be secured to each other and the oil receptacle by suitable means as the rivets 21.

It will be observed that the construction herein illustrated results in an oil receptacle 80 of increased strength, as contrasted with the usual form of non-cellular receptacle, for the reason that the cells act to tie in the opposite walls of the receptacle and support it against rupture from internal pressures; and consequently the switch is enabled safely to 85 interrupt increased values of current.

Said cells are open at the top and bottom and each is adapted to contain a pole of the switch. The lower ends of said cells stop 90 short of the bottom of the oil receptacle 15 whereby to provide an oil space D below the cells which is in communication with all the cells. Similarly the upper end of said cells stop short of the top of the oil receptacle 95 whereby to provide a gas expansion space E above the oil in said cells and under the switch frame; and each cell is in communication with said expansion space. Furthermore, each cell provides for a restricted oil 100 space about the switch-members at the point the circuit-interrupting arc is drawn; and the restricted space may aid materially in quenching the arc; and each pole of the switch has available the entire oil in the 105 switch and the entire gas expansion space of the switch.

Multi-pole switches have been proposed

wherein each pole has been enclosed in separate insulating compartments which are not in free oil inter-communication; and this invention differs from such switches by reason of the free oil communication between the compartments below the oil level therein, the gas expansion space above the oil common to all compartments, and the internally-reinforced structure of the oil receptacle 10 wherein the cells are tied together and to the walls of the oil receptacle and serve to support the walls against rupture from elevated internal pressure.

The invention may be contained in other 15 embodiments without departing from the spirit thereof.

I claim:

1. A multi-pole electric switch including an oil receptacle having a plurality of vertically disposed and laterally spaced solid 20 partition walls terminated a substantial distance below the top and above the bottom of the receptacle and dividing the interior of the receptacle into a plurality of laterally 25 independent and adjacent compartments each of which is adapted to surround a set of switch-members, and said compartments being freely open to the interior of the receptacle and to each other over the tops and 30 also under the bottoms of said partition walls, a switch frame comprising a cover for said receptacle, a plurality of sets of stationary and movable switch members carried by said frame and extended through the 35 open tops of said compartments into the interiors thereof and terminated short of the open bottoms thereof.

2. An oil receptacle for a multi-pole electric switch having a plurality of vertically-disposed and laterally spaced solid partition walls terminated a substantial distance below the top and above the bottom of the receptacle and dividing the interior of the receptacle into a plurality of laterally independent and adjacent compartments each of 45 which is adapted to surround a pole of the switch, and said compartments being freely open to the interior of the receptacle and to each other over the tops and also under the bottoms of said partition walls.

3. A multi-pole electric switch having a cellular oil receptacle, each cell being freely open at the top and bottom and adapted to contain a pole of the switch, means to provide a gas expansion space of substantial height above and common to all cells and in free communication therewith through the open tops thereof, and means to provide

an oil-containing space of substantial depth below and common to all cells and in free communication therewith through the open bottoms thereof.

4. A multi-pole electric switch having an approximately square oil receptacle, a plurality of approximately oval cells contained in said receptacle and open to said receptacle at the tops and bottoms and a switch pole contained in each cell.

5. An oil receptacle for a multi-pole electric switch having a plurality of vertically-arranged cells having circularly formed ends and each adapted to contain a pole of the switch, said cells arranged with open tops and bottoms and spaced between the top and bottom of the oil receptacle and means fixedly uniting the walls of said cells with each other and the walls of the oil receptacle.

6. An oil receptacle for a multi-pole electric switch having tension-members extended through the oil space therein and secured to opposite walls of the receptacle, said tension members also comprising separating partitions between the switch poles.

7. An oil receptacle for an electric switch having its opposite side walls tied in internally below the oil level in the horizontal plane of the arc and at one side of the arc and conductor zones.

8. A multi-pole electric switch having an oil receptacle adapted to contain the switch-members having tie-members extended across the oil space therein between the poles of the switch and fixed to opposite walls of the receptacle whereby to strengthen the receptacle to resist internal pressures.

9. An oil receptacle for an electric switch having side walls and a plurality of cells open at the top and bottom received in said receptacle intermediate the top and bottom thereof, the walls of said cell being secured fixedly to each other and to the side walls of the receptacle.

10. An oil receptacle for an electric switch having side walls and a plurality of cells cylindrically-formed at their opposite ends and open at the top and bottom received in said receptacle intermediate the top and bottom thereof and in contact with each other and the side walls of the receptacle, and means uniting the walls of said cells and said receptacle fixedly together.

In testimony whereof, I have signed my name to this specification.

GEORGE A. BURNHAM.
